[57] **CLAIM**

The ornamental design for a bicycle reflector, as shown and described.

DESCRIPTION

FIG. 1 is a perspective view of a bicycle reflector in accordance with this invention;
FIG. 2 is a side elevational view thereof, with the opposite side being a mirror image;
FIG. 3 is a top view of the bicycle reflector;
FIG. 4 is a bottom view of the bicycle reflector;
FIG. 5 is an end view of one end of the bicycle reflector;
FIG. 6 is an end view of another end of the bicycle reflector;
FIG. 7 is one perspective view of the coiled locked form of the bicycle reflector;
FIG. 8 is another perspective view of the coiled locked form of the bicycle reflector;
FIG. 9 is side elevational view thereof, with the opposite side being a mirror image, with the reflector shown in a coiled position;
FIG. 10 is a top view, as in FIG. 4, but of the coiled locked form of the bicycle reflector; and,
FIG. 11 is a bottom plan view thereof, with the broken line showing for illustrative purposes only and forming no part of the claimed design.
